(57) **CLAIM**

The ornamental design for a scraper tool, as shown and described.

DESCRIPTION

FIG. 1 is a perspective view of the scraper tool;

FIG. 2 is a front view of the scraper tool;

FIG. 3 is a rear view of the scraper tool;

FIG. 4 is a right side view of the scraper tool;

FIG. 5 is a left side view of the scraper tool;

FIG. 6 is a top view of the scraper tool; and,

FIG. 7 is a bottom view of the scraper tool.

The broken lines in the drawings depict portions of the design that form no part of the claim.
